[57] CLAIM

The ornamental design for a picket, as shown and described.

DESCRIPTION

FIG. 1 is an elevational view of a picket according to my new design;

FIG. 2 is an enlarged elevational view of the upper portion of the picket of FIG. 1;

FIG. 3 is a side view of the picket of FIG. 2;

FIG. 4 is a top view of the picket of FIG. 2; and

FIG. 5 is an enlarged bottom view of the picket of FIG. 1.
